UNITED STATES PATENT OFFICE.

NELSON GIBBONS, OF TISKILWA, ILLINOIS.

HALTER.

SPECIFICATION forming part of Letters Patent No. 487,145, dated November 29, 1892.

Application filed May 27, 1892. Serial No. 434,536. (No model.)

To all whom it may concern:

Be it known that I, NELSON GIBBONS, a citizen of the United States, residing at Tiskilwa, in the county of Bureau and State of Illinois, 5 have invented certain new and useful Improvements in Halters; and I do hereby declare the following to be a full, clear, and exact description of the invention, such as will enable others skilled in the art to which it app- 10 pertains to make and use the same.

My invention has relation to halters, and among the objects sought to be attained are to dispense with the use of the ordinary buckle-piece and buckle usually employed for connecting the crown-piece to the ring joining the cheek and throat straps and cause said crown-piece to pass through the said ring and be connected to the remaining portion of itself, whereby the frequent splitting or break- 15 ing of the crown-piece, as usually attached, is avoided; also, to provide in a halter an im- proved means for connecting the end of the crown-piece to itself after having been passed through the ring, whereby a more substantial 20 connection is made and more readily operated to secure or free the end of said crown-piece; and with the above objects in view my in- 25 vention consists in the construction, arrange- 30 ment, and combination of parts, as herein- after fully described, illustrated in the accom- 35 panying drawings, and pointed out in the ap- pended claim.

In the drawings, Figure 1 is a perspective view of my improved halter, showing the manner of applying the crown-piece and also showing in dotted lines the usual buckle-piece and buckle employed. Fig. 2 is a detail view of the crown-piece detached, showing the im- 40 proved connecting means.

40 A indicates an ordinary five-ring halter, comprising the nose-strap *a*, cheek-straps *b b*, throat-latch *c*, and jaw-strap *d*, all being attached to the rings *e e' e'' e''' e''''* in the manner shown in the drawings.

45 *f* indicates the crown-piece, which at one end is connected to the ring *e''*.

To the jaw-strap *a* is attached an ordinary hitching-strap *g*.

50 In the ordinary construction of halters it has been customary to removably attach the free end of the crown-piece *f* to the ring *e'*

by means of a buckle carried by a buckle-piece secured to said ring, the free end of the crown-piece being provided with a number of openings to receive the buckle-tongue. 55 Such buckle-piece and buckle I show in dotted lines in the drawings.

The described mode of attaching the crown-piece has many objectionable features, chief among which is that when much strain is ex- 60 ereted upon the said buckle-piece and buckle the tongue of the latter will cause splitting of the crown-piece.

In my invention I dispense with the use of the buckle-piece and buckle and attach the 65 free end of the crown-piece by passing the same through the ring *e'* (after having first been passed over the head of the animal) and then attaching said free end of the crown-piece to itself. In other words, I cause the 70 crown-piece to be doubled back upon itself after passing through the ring. By this lapping of the crown-piece any strain that may be exerted upon the ring *e'* would be removed from the point at which the free end of the 75 crown-piece is secured to the latter itself.

For connecting the end of the crown-piece to itself after passing through the ring I em- 80 ploy the means shown in the drawings, and which consists, essentially, of a metallic hook 85 or fastener *B*, the rear portion of the shank *h* of which is broadened, as at *h'*, and the lat- 90 ter is secured to the end of the crown-piece by means of rivets *i*. The forward portion of the shank tapers gradually and terminates in a *T*-head *k*. The crown-piece is provided at suitable intervals with longitudinally-ar- 95 ranged slots *l*, which are adapted to permit the passage therethrough of the said *T*-head *k*.

When it is desired to attach the free end 90 of the halter, the said end is passed through the ring *e'* and then doubled upon itself and the same turned or twisted to bring the *T*-head in position to be passed through one of the slots *l* in the crown-piece, and after said head has been passed through the slot it is turned to cause the said head to lie across the slot, thus effecting the fastening. To release the end of the crown-piece, the latter or the hook is turned to bring the *T*-head in align- 100 ment with the slot, when it may be withdrawn therethrough and also through the ring *e'*.

By providing a series of slots *l* the crown-piece may be adjusted to suit different sizes of animals' necks.

As will be seen, my improved hook or fastener permits of the ready attachment of the crown-piece to and disconnection from the ring. Although I show the said hook adapted for use in connection with halters, it may be used with various other pieces of harness, wherever it is desired to connect one portion to another.

What I claim, and desire to secure by Letters Patent, is—

The combination, with an ordinary halter of the class described, comprising the cheek and throat straps and the rings *e*³ *e*⁴, connect-

ing the same, of the crown-piece *f*, secured at one end to the ring *e*³, a series of openings *l* in said crown-piece, and a metallic hook *B*, secured to the other end of the crown-piece 20 and having a T-head, said end of the crown-piece and the hook being passed through the ring *e*⁴ and doubled back to form the loop described and said T-head being passed through one of the openings *l*, for the purpose specified. 25

In testimony whereof I affix my signature in presence of two witnesses.

NELSON GIBBONS.
